(57) **CLAIM**

The ornamental design for a rifle barrel and stock assembly, as shown and described.

DESCRIPTION

FIG. 1 is a front top perspective view of a firearm barrel and stock assembly according to the new design;

FIG. 2 is rear bottom perspective view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a front elevation view thereof; and,

FIG. 8 is rear elevation view thereof.

All broken lines shown in the drawings are for environmental purposes only and form no part of the claimed design.
